CHUCK FOR JEWELERS' LATHES

Filed May 15, 1922

Patented Sept. 16, 1924.

UNITED STATES PATENT OFFICE.

JAMES E. STEWART, OF MARYVILLE, MISSOURI, ASSIGNOR OF ONE-THIRD TO L. H. LUDWIG, OF KANSAS CITY, MISSOURI, AND ONE-THIRD TO HERBERT L. RAINES, OF MARYVILLE, MISSOURI.

CHUCK FOR JEWELERS' LATHES.

Application filed May 15, 1922. Serial No. 561,194.

To all whom it may concern:

Be it known that I, JAMES E. STEWART, a citizen of the United States, and resident of Maryville, county of Nodaway, State of Missouri, have invented a certain new and useful Improvement in Chucks for Jewelers' Lathes, of which the following is a complete specification.

This invention relates to chucks and more especially to chucks for jewelers' lathes, my object being to produce a simple inexpensive chuck by which it is possible to quickly and accurately center watch staffs and the like preparatory to repair thereof or for any other purpose.

With this general object in view the invention consists in certain novel and useful features of construction and combinations of parts as hereinafter described and claimed; and in order that it may be fully understood, reference is to be had to the accompanying drawing, in which:

Figure 1 is a side elevation of a chuck embodying the invention;

Figure 2 is a central vertical longitudinal section of the chuck, but showing certain clamping elements thereof in side elevation;

Figure 3 is a front view of the chuck;

Figure 4 is a horizontal longitudinal section of a fragment of the chuck with the pump center reversed in position to centralize the front plate on the chuck;

Figure 5 is a section taken on the line V—V of Figure 2;

Figure 6 is a detail perspective view of one of the slide clamps of slightly modified construction from that shown in the preceding figures;

Figure 7 is a front view of a different form of the chuck construction; and

Figure 8 is a view partly in side elevation and partly in section of the construction shown by Figure 7.

Referring to the drawing in detail, where like reference characters identify corresponding parts, 1 indicates the stem of a chuck for jewelers' lathes and the like, provided at its front end with a hollow head comprising a rear or disc portion 2, a front

or ring portion 3, and a pair of diametrically-opposite portions 4 connecting the rear and front portions, the construction described comprising a head which is of skeleton form as well as hollow so that the work can be more readily inserted and kept under observation.

The stem and the rear portion of the head are formed with a central longitudinal bore 5 wherein fits a reversible pump center 6, the same being provided at one end as customary with an axial socket 7. It is also provided at its opposite end with an axial pointed end 8 and adjacent the same is threaded so that when the pointed end is not in use it may be enclosed by a projecting cap 9 screwed upon the threaded portion. Near its opposite ends the pump center is formed with flattened faces 10 and 11 with either of which an eccentric clamping rod 12 mounted in the stem is adapted to engage 70 for holding the pump center rigidly in the desired position, the rod having a handle 13 for convenience of operation.

To close the open end of the hollow head, a front plate 14 is provided, the same having a raised central or body portion and being formed in the center thereof with an orifice 15 for a purpose which will herein-after appear. It is also provided in its edges with diametrically-opposite notches 16. At 80 diametrically opposite sides the head is formed with longitudinal dove-tail grooves 17 for registration with the notches 16 in the front plate, and the rear portion of the head is circumferentially threaded as at 18 for engagement by a knurled nut 19.

A pair of slides for clamping the front plate 14 rigidly in position, comprise rear portions 20 and front headed portions 22 extending through the notches of the head,— 90 the portions 20 engaging the grooves with a dove-tail relation and being provided in their outer faces with transverse channels 21 to receive the knurled nut 19 so that when the latter is turned to move forward or rearward on the threaded head, corresponding endwise movement shall be imparted to the slides, to cause the heads thereof to move

- forward from or rearward toward the front plate. In Figures 1 to 5 inclusive, the front portions of the slides are pivoted as at 23 to the rear portions, and springs 24 hold the front portions yieldingly in the grooves 17. In Figure 6, the slides will be resilient so that the front portions can have a corresponding or hinge movement relative to the rear portions. In both constructions, it will be obvious that rotative movement of the nut 19 is employed to cause the heads of the slides to clamp the front plate rigidly in position upon the chuck head, and that sufficient reverse movement of the nut will remove the pressure of the slide heads from the clamp plate and permit said heads or one of them, to be swung outward sufficiently to permit of the quick and easy removal of the front plate.
- 20 In the construction shown by Figures 7 and 8, the front plate 14 is secured in position by headed bolts 25 extending through the notches 16 and into threaded sockets 26 formed in the ring portion 3 of the head, the notches 16 being sufficiently large as is true also in the construction previously described, to permit of slight adjustments of the front plate to center the orifice thereof axially of the stem preliminary to screwing the bolts 25 tightly in position. The removal of one bolt 25 and the partial unscrewing of the other provides for the quick removal of the front plate.
- Assuming that it is desired to place the front plate in proper position with respect to the axial center of the chuck, the pump center is arranged in the latter as indicated by Figure 4. The front plate is then fitted against the front end of the head with its orifice receiving the pointed end 8 of the pump center. The front plate is then clamped firmly in position by turning the nut 19 or the bolts 25 as the case may be. The pump center is then removed and reversed so as to dispose its socketed end in the head as indicated by Figure 2. A watch staff or the like is then arranged in the head with one pivot end in the socketed end of the pump center and the other end fitting in the orifice of the plate 14. The pump center is then clamped firmly in position by means of the clamp 12 and a drill as indicated at 27, may be employed to drill a socket in the front end of the staff for the reception of a pivot to take the place of the pivot end of the staff which it is assumed, has been broken off and needs replacing.
- It is desirable that the front plate shall be made as thin as possible and perfectly flat, as a great many large size balances are arranged so close to the top of the staff that the wheel will ride on its rim before the pivot reaches the orifice in the front plate. It is desirable to have the central portion of said plate raised because the pro-

vision of notches in the margin or flange will not weaken the plate to the same extent as would be the case if the plate lacked the raised portion. After the repair has been made, the clamping pressure on the plate can be relaxed as hereinbefore explained, to permit the plate to be removed or drop out.

From the above description it will be apparent that I have produced a chuck embodying the feature of advantage set forth as desirable in the statement of the object of the invention, and which is susceptible of modification in minor particulars without departing from the principle of construction and mode of operation involved.

I claim:

1. A chuck having a stem provided at one end with a hollow head open at its front end, a plate for fitting on the front end of the head over the open end thereof and provided with a bearing orifice for axial alinement with the axis of the stem, a pump center fitting axially in the stem and axially pointed at one end for engaging with the orifice of the plate to center the same, and means for clamping the plate in place.

2. A chuck having a stem provided at one end with a hollow head open at its front end, a plate for fitting on the front end of the head over the open end thereof and provided with a bearing orifice for axial alinement with the axis of the stem, a reversible pump center fitting axially in the stem and axially pointed at one end and provided with an axial socket in its other end, means to clamp the pump center rigidly in place, with its pointed end engaging the orifice of said plate to center the plate, or its socketed end at the head end of the stem in service position relative to the orifice of said plate, and means for clamping said plate rigidly in place while its orifice is engaged by the pointed end of the pump center.

3. In a device of the character described, a stem having a hollow head open at its front end, circumferentially threaded at its rear end and provided with a plurality of longitudinal grooves, a plate fitting against the front end of the head and provided with a central orifice and marginal notches, means for centering the plate with respect to the center of the stem, slides fitting in the grooves of the head and notches of the plate, having heads engaging the outer face of the plate and transverse channels adjacent the threaded portion of the head, and a nut engaging the threaded head and the channels of the slides.

4. In a device of the character described, a stem having a hollow head open at its front end, circumferentially threaded at its rear end and provided with a plurality of longitudinal grooves, a plate fitting against the front end of the head and provided with a central orifice and marginal notches,

means for centering the plate with respect to the center of the stem, slides fitting in the grooves of the head and notches of the plate, having heads engaging the outer face 5 of the plate and transverse channels adjacent the threaded portion of the head, and a nut engaging the threaded head and the

channels of the slides, said slides being capable of being sprung at their front ends out of the notches of the plate. 10

In witness whereof I hereunto affix my signature.

JAMES E. STEWART.
